CLAIM

The ornamental design for a display screen with a transitional graphical user interface as shown and described.

DESCRIPTION

1. Display screen with transitional graphical user interface

1.1 : Front

1.2 : Front

1.3 : Front

The broken lines showing portions of the graphical user interface form no part of the claimed design.

The appearance of the transitional image sequentially transitions between the images shown in Figs. 1.1-1.3. The process or period in which one image transitions to another forms no part of the claimed design.
